UNITED STATES PATENT OFFICE.

ANTHONY GEORGE, OF GRENOVA, NORTH DAKOTA.

COMBINATION TOOL.

Application filed January 3, 1922. Serial No. 526,693.

To all whom it may concern:

Be it known that I, ANTHONY GEORGE, a citizen of the United States, residing at Grenora, in the county of Williams and State of North Dakota, have invented a new and useful Combination Tool, of which the following is a specification.

The present invention is designed to provide a combination tool or geometrical instrument of the multipivoted straight edge type, including a leveling feature, and level sighting feature. The primary object of the invention is the provision of a tool of this character of the folding rule type that is adapted for various uses, constructed of a minimum number of parts, which may be extended as a straight edge or folded and adjusted for use as a square, or as an angle or miter-square. By the utilization of the subject matter of my invention as physically embodied, the amateur who is unfamiliar with the uses of the usual steel square, may with accuracy and convenience lay off work. And the compactly folded device provides a pocket tool which may be carried with convenience, and be substituted for various tools now in use.

In the accompanying drawings I have illustrated one complete example of the physical embodiment of my invention including, in addition to the spirit level and sight level, a protractor, in which the parts are combined and arranged according to the best mode I have thus far devised for the practical application of the principles of my invention.

Figure 1 is a plan view of the entire device embodying my invention, the end blades being turned up at right angles or perpendicular to the intermediate blade, for convenience of illustration.

Figure 2 is an edge view of Fig. 1.

Figure 3 is a sectional view taken on line 3—3 of Fig. 1.

Figure 4 is a diagrammatic view, in miniature, showing the tool extended as a straight edge.

In the preferred form of the invention, the blade sections 1, 2, and 3 are preferably of steel, with scale markings thereon, in this instance, showing inches and divisions thereof, but it will be understood that the scales or markings may be varied, and different arrangements may be made on the several blade sections, as desired, and I do not there-

fore limit myself to the use of the scale markings shown.

The blades or blade sections have a pair of pivot pins or screws 4 and 5, and by means of the thumb nuts 6 and 7 on the respective screws, the end blade sections may be adjusted to various angles with relation to the intermediate section 1, or the end sections may be turned to aligned position, as in Fig. 4, to form a straight edge. In any of these adjusted positions the end blades may be secured in rigid relationship to the intermediate blade by turning tight the thumb-nuts.

For laying off angles at various degrees with relation to the intermediate blade, I utilize a protractor 8, which is riveted at 9 to the intermediate blade, and is also secured to said blade by the screw 4 and its nut 6. The protractor is rigid with the intermediate blade, and the end blade 2, which is pivoted on the screw 4 at the center of the protractor, may be utilized to mark off angles as desired. Because of the limited space I have purposely omitted from the protractor the angle figures, but it will be understood that any well known type of protractor may be used and rigidly secured to the intermediate blade as shown.

On the end section 3, I preferably use a detachable spirit level 10, which extends longitudinally of the blade section and is provided with end caps or cups 11 fashioned with perforated ears 12 extending outwardly therefrom. At one end of the spirit level the pivot screw 5 and thumb nut 7 are used to retain the spirit level, while at the other end of the level a complementary screw 13 and nut 14 are employed. The spirit level fits neatly in its end caps with sufficient friction to retain it in adjusted position, but its fit is loose enough to permit turning of the level within its end caps, so that, when not in use, as in Figure 4, the glass may be turned around toward the blade section 3, for protection.

On the end section or blade 2 I provide a sighting device for use in leveling and determining angles with reasonable accuracy, at various distances. The sighting device comprises two spaced sights 15 and 16, the former being used as the front sight and the latter as the rear sight, and the sight opening 17 in the front sight is preferably larger than the sight opening 18 in the rear sight.

piece, for convenience in sighting. Each of the sight pieces comprises a flat disk or plate 19 with the sight opening therein, and the front sight disk has a wire 15' across its opening to be used as a cross wire in centering the sight openings. The flat plates are each fashioned with a bracket arm 20, angular in shape and the bracket arm is provided with an interiorly threaded sleeve 21 for the reception of the clamp screw 22. In the drawings it will readily be seen that the two sight openings are aligned, the plates being attached at spaced distance along the edge of the end blade section 2. By means of the screws 22 these sight pieces are rigidly attached to the end section 2, the screws passing through holes or openings in the blade section for that purpose.

From the above description taken in connection with my drawings it will be apparent that I have provided a combination tool

which fulfills the objects and purposes set forth in my statement of invention, and while I have shown a preferred embodiment of the invention, it will be understood that various changes and alterations may be made therein, within the spirit of my invention, without departing from the scope of my claim. 25

Having thus fully described my invention, what I claim and desire to secure by Letters Patent is:—

The combination with an intermediate blade section and pivoted end sections one of said sections having a threaded opening, 35 of a pair of sight pieces with sight openings, said pieces each comprising a disk and an attaching bracket and a clamp screw in said bracket engaging said threaded opening in the end section.

ANTHONY GEORGE.
